[57] **CLAIM**

The ornamental design for combined clock and photograph holder, as shown and described.

DESCRIPTION

FIG. 1 is a perspective view of a combined clock and photograph holder showing my new design;
FIG. 2 is a front elevational view thereof;
FIG. 3 is a rear elevational view thereof;
FIG. 4 is a left elevational view thereof; the opposite side being a mirror image of the shown;
FIG. 5 is a top plan view thereof; and
FIG. 6 is a bottom plan view thereof; and,
FIG. 7 is the perspective view thereof in which combined clock and photograph holder is in an open position, showing the clock separately for ease of illustration, drawn on an enlarged scale.
